UNITED STATES PATENT OFFICE.

LOUIS WILLIAMS, OF DENVER, COLORADO.

LOCKING DEVICE FOR SATCHELS, &c.

1,034,050.

Specification of Letters Patent. Patented July 30, 1912.

Application filed November 28, 1911. Serial No. 662,869.

To all whom it may concern:

Be it known that I, LOUIS WILLIAMS, a citizen of the United States, residing at Denver, in the county of Denver and State 5 of Colorado, have invented certain new and useful Improvements in Locking Devices for Satchels, &c., of which the following is a specification.

This invention relates to locking devices 10 for checking satchels and similar articles.

The purpose of the invention is to provide a device of this kind which is simple in construction, comprises only a few substantial parts and which cannot readily get out of 15 order or fail to operate when desired. In devices of this character it is essential that the device shall always operate to release the article checked, as a failure to release the article after it has been checked causes 20 annoyance and unless thoroughly reliable such devices cannot readily be sold.

The device shown in the accompanying drawing is constructed with a minimum 25 number of parts of ample strength and because of its simplicity is not liable to get out of order.

In the accompanying drawing,—Figure 1 is a perspective view of a lock made according 30 to my invention, attached to a support, the locking bolt being shown in closed position with a satchel or grip secured by a chain; Fig. 1^a is a side view of the key for releasing the bolt; Fig. 2 is a rear view of the lock, the key being shown in position 35 and the slide which carries the bolt being released; and, Fig. 3 is a vertical section taken in the plane of the locking bolt, the latter being shown in its closed position.

Referring to the drawing, A indicates a 40 suitable metal casing, preferably of sheet steel and of rectangular form. This casing is provided with suitable bolt holes 1, through which bolts 2 may be passed for securing the casing to a suitable support. 45 Upon the front of the casing and near its lower end is secured a metal plate 4 having an outwardly projecting tongue 5 provided with an opening 6 which forms an eye to receive a bolt 7 secured to a slide 8 arranged 50 within the casing and movable vertically through suitable guide openings in its upper and lower ends. One end of a chain 9 is connected to the plate 4 by a suitable attaching device 10 and the other end of the 55 chain is provided with a ring or loop 11, through which the bolt 7 may extend, when

the bolt is in closed position, as shown in Figs. 1 and 3. The chain may, prior to closing the bolt, be looped through the handle of a satchel G or around any other 60 object which is to be secured.

A spring 12 attached to the upper end of the casing and to a stud 13 on the slide 8 normally tends to move the bolt 7 away from the eye in the part 5. The slide has 65 a cut out portion 14 which provides shoulders at the ends of said cut out portion adapted to engage a stop 15 which limits the movements of the slide. A notch 16 is also cut in the edge of the slide near its upper end. A locking device C is pivoted 70 upon a pin 17, within the casing, this locking device comprising arms 18 and 19 arranged at right angles to one another. The arm 18 has a tooth or detent 20 adapted to 75 engage the notch 16 when the slide is moved downward until its shoulder 14^a engages the stop 15. The tooth 20 normally rests against one edge of the slide as shown in Fig. 2 and the tooth 21 is thereby held in 80 engagement with a shoulder 22 in the key B so as to lock the key in the casing. A spring 23 normally presses the tooth 20 against the slide, and it will be seen that when the slide is pushed downward the 85 spring 23 will automatically force the arm 18, to the right, in Fig. 2, so that the tooth 20 will enter the notch 16 and lock the slide, while the tooth 21, will be moved away from the shoulder 22 and unlock the key. The 90 key is adapted to fit into a key sheath 24 which extends through the upper wall of the casing and the end portion 19^a of the arm 19 extends beneath the lower end of the key so as to be engaged thereby when the 95 key is pushed downward to its fullest extent.

Normally the bolt and slide are in their upper positions and the key is locked within its sheath. In order to secure a satchel or other article, the chain is looped around the handle or other part of the article and the ring on the end of the chain is passed over the tongue 5 and the bolt and slide are depressed by applying pressure to the finger piece 7^a, at the upper end of the bolt. 100 The bolt passes through the ring on the end of the chain and the locking member C is moved by the spring 23 so as to cause the tooth 20 to engage the notch 16 and to remove the tooth 21 from the shoulder 22 in 105 the key. The key may then be taken out and retained by the person checking the 110

article until it is desired to release the latter. When it is desired to release the article, the key is inserted into its sheath and pressed downward against the tripping arm 19 which causes the tooth 20 to move out of engagement with the notch 16 and causes the tooth 21 to extend above the shoulder 22 on the key. The spring 12 instantly moves the slide upwardly throwing the bolt 10 to open position, and the tooth 20 then rests against the edge of the slide and holds the tooth 21 in engagement with the key.

Where a plurality of locking bolts are used, the casings are appropriately numbered and the keys for the several locks are correspondingly numbered. In the drawing, the casing and key, in Figs. 1 and 1^a, are numbered 25 for illustration. Each key is designed to operate only the lock in one casing, so that only the individual holding that key may unlock the article from the correspondingly numbered casing.

What I claim is:—

1. In a locking device for parcels, etc., 25 a casing having an eye, a slide movable in said casing and a bolt on said slide adapted to engage said eye, a spring for moving said slide to disengage the bolt from the eye, said slide having a notch near one end, a key-sheath projecting into the casing, a key fitting said sheath and having a shoulder, a locking and releasing device pivoted within the casing, said device comprising two arms, one arm projecting between the slide and the 30 key-sheath and having a tooth on one side

for engaging the notch in the slide and a tooth on the opposite side for engaging the shoulder on the key, the other arm extending into the plane of the key at the inner end of the key-sheath, and a spring normally pressing said first-mentioned arm toward the slide. 40

2. In a locking device for parcels, etc., a casing having an eye, a slide movable in said casing and a bolt on said slide adapted 45 to engage said eye, a spring for moving said slide to disengage the bolt from the eye, said slide having a notch near one end and having a part cut out near its opposite end to provide shoulders, a fixed stop between said shoulders, a key-sheath projecting into the casing, a key fitting said sheath and having a shoulder, a locking and releasing device pivoted within the casing, said device comprising two arms, one 50 arm projecting between the slide and the key-sheath and having a tooth on one side for engaging the notch in the slide and a tooth on the opposite side for engaging the shoulder on the key, the other arm extending into the plane of the key at the inner end of the key-sheath and a spring 55 normally pressing said first-mentioned arm toward the slide.

In testimony whereof I affix my signature, 60 in presence of two witnesses.

LOUIS WILLIAMS.
